Primary Examiner — Melanie Pellegrini*(74) Attorney, Agent, or Firm* — Hovey Williams LLP(57) **CLAIM**

The ornamental design for a charm bracelet, as shown and described.

DESCRIPTION

FIG. 1 is a front, top perspective view of a charm bracelet embodying our new design;

FIG. 2 is a rear, top perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof; and,

FIG. 8 is a left side elevational view thereof.

The broken lines represent portions of the charm bracelet which form no part of the claimed design.
